UNITED STATES PATENT OFFICE.

EDMUND S. DICKEY, OF BALTIMORE COUNTY, MARYLAND, ASSIGNOR TO AMERICAN METER COMPANY, INC., OF NEW YORK, N. Y., A CORPORATION OF DELAWARE.

GAS-METER.

1,305,646.

Specification of Letters Patent. Patented June 3, 1919.

Application filed March 20, 1918. Serial No. 223,577.

To all whom it may concern:

Be it known that I, EDMUND S. DICKEY, a citizen of the United States, residing in the county of Baltimore and State of Maryland, have invented certain new and useful Improvements in Gas-Meters, of which the following is a specification.

This invention relates to improvements in dry type gas meters, and more particularly 10 to the valve construction of such meters.

In the present style of meters of two valve construction, the tendency has been to increase the size of the valves with the object of securing the greatest possible valve area 15 for the quick intake and discharge of gas, for the purpose of increasing the meter capacity, that is to say, increasing the number of cubic feet of gas passed by the meter in a given time. Obviously this increase in the 20 size of the valve has its limitations, and becomes practically prohibitive, for various reasons in connection with present form of valve construction.

It is my purpose primarily, by these 25 improvements, to provide four valves in two valve units, that is to say, two single valves, each formed into a double valve, and constituting a single valve unit, whereby I obtain the marked advantage of getting a valve 30 area in a single meter equivalent to four valves in a meter, thus obviously enabling the meter to quickly take and discharge gas with corresponding increase in the capacity of the meter.

The construction is such that the valves 35 can be conveniently positioned on the valve table and connected by suitable channels and adapted to serve two diaphragms in a single meter, and by other channel connections, 40 serve or control four diaphragms in one meter.

In meters for which the valve construction about to be described is especially designed, there is a central partition in the 45 meter casing, dividing it into diaphragm compartments, usually one diaphragm in each compartment, and the valve units, according to my construction, are located one on each side of the partition, and may be 50 adapted, by suitable channel connections, as just stated, to serve or control either one diaphragm in each compartment, or two in each compartment, as the case may be.

The angle of mounting the valves upon the 55 valve table, in my improvements, does not

differ from that of mounting the valves in the ordinary two valve style, and in both instances, the valves are mounted at 90° for reciprocal action in coördination with the diaphragms on each side of the meter partition, which manner of mounting is to prevent the rotary parts of the meter from at any time being on dead center.

Another object of my invention is to provide a valve in which, or through which, 65 double valve area is obtained, with the use of but one crank and one valve arm, and this without increase in the valve stroke, or length of travel of the valve.

Another object of the invention is to so 70 construct the valve and valve seat, that double the valve area is obtained with the consequent advantages of quick intake and discharge of gas, and corresponding increase 75 in meter capacity, with only approximately one-half increase in friction of the valve in its reciprocation, over two separate single valves now commonly employed in two valve meter construction—a very important consideration when it is realized that the elimination of friction reduces the resistance of 80 the meter resulting in increased capacity of the meter, under a given loss of pressure in operation. In the construction wherein I greatly reduce friction, in proportion to the 85 valve area, there is incident a reduction in the number of valve surfaces of the valve seat, thus reducing the number of grinding surfaces between the seat and the valve, which reduces the liability of the so-called 90 cutting action on the valve faces, due to the sliding motion of the valve.

A very important consideration in valve construction, particularly in the construction 95 of valves for large meters, is the tendency of these valves to warp or otherwise become distorted, thus destroying the perfect fit which is required between the surfaces of the valves and the valve seats, with the consequent leakage of gas through the valves. 100 The enlargement of valve area obtained in my valve construction would be practically impossible in a single valve, due to this warpage or distortion, but which is largely overcome in the valve construction about to 105 be described.

A still further object of the invention is to so construct and arrange the valves as to eliminate the necessity of duplication of 110 valve wrist pins and valve arms, and the

necessity for the use of double or triple cranks on the valve operating shaft for effecting multi-valve movement.

A still further object is to provide accurate guiding means for the valve on its seat, and to so construct the guides that they will be "self-cleaning" and kept free from the gumming or sticking effects which would otherwise result from the gas condensates or heavy oils.

In the accompanying drawings, there is shown only enough of the meter casing, valve table and channels to show the relative position of the valves to these parts, the invention disclosed in this application, as before stated, residing more particularly in the valve construction, and it will be understood that suitable channels may be provided below the valve table and in communication with the various ports in the valve seat, so that the valves may be adapted for supplying, under the control of a single valve arm for each valve, either two diaphragms located one in each diaphragm compartment, or two diaphragms in each compartment.

Figure 1 is a top plan view of a meter with the top plate removed and the valve housing broken away to show the position of the valves on the valve table.

Fig. 2 is a cross section of one of the valves shown in Fig. 1, taken on line *a*—*a*, showing the valve in position on its seat, wherein communication is established between a diaphragm channel and the outlet channel, and between the space above the valve table and the casing, or diaphragm compartment, below the casing, the wrist pin in this view, being shown on the front flange of the valve.

Fig. 3 is a longitudinal section taken on line *b*—*b* of one of the valves shown in Fig. 1, showing the manner of supporting and guiding the valve on the valve seat.

Fig. 4 is a top plan view of a valve seat. Fig. 5 is a cross section of a valve shown in Fig. 1, the position being that in which the communication between the diaphragm and outlet, and between the casing or a diaphragm compartment and outlet, is cut off, the wrist pin in this form, being shown located centrally in the dome portion of the valve.

Fig. 6 is a similar view of one of the valves shown in Fig. 1, slightly modified in the particular that the wrist pin for connection with the valve operating arm, is shown on the rear flange or ledge of the valve, the position of the valve in this form being such that communication between the space above the valve table and a diaphragm, and the space between the meter casing and the outlet, is established.

Referring to the drawings, the numeral 1 designates the meter casing, which may be, in all essential respects, like meter casings

in common use, except in the particular of external dimensions, which I am able to greatly reduce, relative to the meter capacity, by reason of the novel construction and arrangement, the meter casing being substantially of the same dimensions as the ordinary meter casing, with the exception of slight increase in the comparatively unimportant dimension of depth. The numeral 2 designates the back and 3 the front of the casing, and 4 the sides, which sides are provided with the usual intake connection 5, and outlet connection 6.

The numeral 7 designates the valve table and 8 the flagstaffs, extending through the table from the bottom of the meter, not further illustrated in this application, and it need only be said here that these staffs are connected by suitable flags to diaphragms below the table, and are designed to carry the usual arms linked to the valve operating shaft 9, which, in this instance, is provided with a single crank 10, to which are connected the valve arms 11, which are in turn connected in the form shown in Figs. 1 and 2, to wrist pins 12, on the valves.

Each valve and its seat, is identical with the other, and consequently a detail description of one will serve as a description of the other. The numeral 13 designates the valve, 95 oblong and generally rectangular in shape, and formed with a dome portion 14, and front and rear flanges 15 and 16, the flanges serving, in the reciprocation of the valve, to cover and uncover the diaphragm and casing ports 17 and 18, respectively in the valve seat 19, to alternately establish communication between the diaphragm channels 17' and outlet channel 18' and between the meter casing or diaphragm compartments, 100 and the outlet, through the outlet port 20 in the valve seat, which port 20, as shown in Figs. 2 and 6, is never entirely closed, there being shown in these figures two opposite extreme positions of the valve on its seat.

The valve seat is formed with two parallel side bars 21, front and rear bars 22, and two intermediate bars 23, and a central transverse bar 24, forming between them the diaphragm port 17, the outlet port 20, and the casing port 18. The side bars 21, and bar 24 are extended beyond the bars 22, and the upper surfaces of all of the described bars are smoothly ground to form suitable bearing surfaces for the valve, and the surfaces are all in the same plane. The side bars 21 form bearings for the lower edge 25 of the sides of the valve, and I provide the dome portion of the valve with a central rib 26, which has a bearing upon the bar 24, 120 which rib 26 divides the valve into two compartments 27 and 28, and the bar 24 divides the valve seat.

In the form of valves illustrated, I use in a single meter, two valves and four

diaphragms with suitable channel connections, which is in a given unit, equivalent to four valves in capacity for control of the gas into and out of the meter. In the arrangement just indicated, channels are provided connecting with the diaphragm ports and outlet ports of a valve on one side of the partition, and with corresponding ports of the other valve on the other side of the partition.

10 In adapting the valves for control of two diaphragms, one on each side of the partition, I arrange the channels to serve two diaphragms and their compartments, instead of four diaphragms and their compartments, it being understood, of course, that the flow of gas into and out of the diaphragms and their compartments is controlled through the valves.

20 Having thus fully described my invention, what I claim is:—

1. In a gas meter, in combination, a valve seat whose dimension transverse to the direction of the line of travel of the valve on the seat, is greatly in excess of its length, and having diaphragm, casing, and outlet ports, coextensive with said dimension, whereby greatly increased valve capacity is obtained and a valve on said seat, and means 30 for operating the same.

2. In a gas meter, in combination, a valve seat, whose dimension transverse to the direction of the movement of the valve on said seat is greatly in excess of its length, and having diaphragm, casing and outlet ports, coextensive with said dimension, whereby increased valve capacity is obtained, and a valve adapted to slide on said seat, a valve operating shaft, and connections between the valve and operating shaft.

3. In a gas meter, in combination, a meter casing having a partition therein dividing

it into diaphragm compartments, a valve seat on each side of said partition, each of said valve seats having the dimension transversely of the line of travel of the valve on the seat, greatly in excess of its length, and having diaphragm, casing and outlet ports, coextensive with said dimension, whereby increased valve capacity is obtained, and a valve fitted to slide on each seat, an operating shaft having a single crank and connections between the crank and the valves.

4. In a gas meter, in combination, an oblong valve seat having side bearing bars and a central bearing bar, and diaphragm, casing, and outlet ports, and a valve on said seat having side portions bearing on the side bars and an intermediate rib designed to bear and travel on the central bar.

5. In a gas meter, in combination, a valve seat, a valve table, guide rails located at opposite sides of the valve seat, and separated therefrom and mounted on the valve table, a valve adapted to slide on the valve seat and having brackets coöperating with the guides, whereby the valve is guided on its seat.

6. In a gas meter, in combination, a valve seat, a valve table, a guide rail located at each side of the seat and separated therefrom and mounted on the valve table and provided with a laterally extending upper portion, a valve designed to travel on the valve seat and provided on each side with an angle bracket having a portion underlying the upper portion of the guide rail, whereby the valve is guided on the seat.

In testimony whereof I affix my signature in presence of two witnesses.
